UNITED STATES PATENT OFFICE.

JOHN S. MITCHELL AND SERENUS M. COLBURN, OF MINNEAPOLIS, MINNESOTA, ASSIGNORS TO L. S. DONALDSON COMPANY, OF MINNEAPOLIS, MINNESOTA, A CORPORATION OF MINNESOTA.

DESIGN FOR A STORE-COUNTER.

42,108.

Specification for Design.

Patented Jan. 23, 1912.

Application filed March 2, 1911. Serial No. 611,941. Term of patent 7 years.

To all whom it may concern:

Be it known that we, JOHN S. MITCHELL and SERENUS M. COLBURN, citizens of the United States, residing at Minneapolis, in the county of Hennepin and State of Minnesota, have invented a new, original, and ornamental Design for Store-Counters, of which the following is a specification, reference being had to the accompanying drawing, forming part thereof.

The figure is a perspective view of a store counter showing our new design.

We claim:

The ornamental design for a store counter, as shown.

JOHN S. MITCHELL.
SERENUS M. COLBURN.
